US00D753246S

(12) **United States Design Patent**
Kaye et al.

(10) **Patent No.:** **US D753,246 S**
(45) **Date of Patent:** ** *Apr. 5, 2016

(54) **STRENGTH TRAINING AND STRETCHING MACHINE**

(71) Applicant: **ARQEX OUTDOOR FITNESS SYSTEMS, LLC**, Rye Brook, NY (US)

(72) Inventors: **Eric A. Kaye**, Rye Brook, NY (US); **William C. Cesaroni**, Glenview, IL (US); **Morad Ghasseman**, Oak Park, IL (US); **Brian W. Mathews**, Waterman, IL (US); **Eugene L. DiMonte**, Aurora, IL (US); **Donovan D. Zielke**, Laguna Nigel, CA (US); **Steven M. Lenz**, Naperville, IL (US)

(73) Assignee: **ARQEX OUTDOOR FITNESS SYSTEMS, LLC**, Rye Brook, NY (US)

(*) Notice: This patent is subject to a terminal disclaimer.

(**) Term: **14 Years**

(21) Appl. No.: **29/514,827**

(22) Filed: **Jan. 16, 2015**

Related U.S. Application Data

(63) Continuation-in-part of application No. 13/836,359, filed on Mar. 15, 2013.

(57) **CLAIM**

The ornamental design for a strength training and stretching machine, as shown and described.

DESCRIPTION

FIG. 1 is a perspective view of the strength training and stretching machine in accordance with our design;

FIG. 2 is a front view thereof;

FIG. 3 is a top view thereof;

FIG. 4 is a right side view thereof; and the left side view will be a mirror image thereof; and,

FIG. 5 is a rear view thereof.

1 Claim, 5 Drawing Sheets
